FLUID DISPENSER

Thomas W. Miller, Ashland, Ohio, assignor to
 The Faultless Rubber Company, Ashland, Ohio,
 a corporation of Ohio

Application December 9, 1938, Serial No. 244,809

8 Claims. (Cl. 215—74)

My invention relates to fluid dispensers, more particularly to combined closures and fluid dispensers for containers, and the principal object of my invention is to provide new and improved devices of this character.

In the drawings accompanying this specification, and forming a part of this application, I have shown, for purposes of illustration, embodiments which my invention may assume, and in these drawings:

Figure 1 is a side elevational view of an embodiment of my invention applied to a bottle,

Figure 2 is an enlarged fragmentary vertical sectional view of the embodiment shown in Figure 1,

Figure 3 is a sectional view similar to Figure 2, omitting the bottle, and showing the parts comprising the embodiment in separated relation, and additionally showing means closing the dispenser opening,

Figure 4 is a sectional view similar to Figure 2, showing certain parts in the relation assumed when the dispenser is sealed,

Figure 5 is a side elevational view, illustrating a different embodiment of my invention applied to a bottle,

Figure 6 is an enlarged fragmentary vertical sectional view of the embodiment shown in Figure 5,

Figure 7 is a sectional view similar to Figure 6, omitting the bottle, and showing the parts comprising the invention in separated relation, and

Figure 8 is a sectional view corresponding generally to the line 8—8 of Figure 6, but showing the valve in unseated relation.

The embodiment of the invention shown in Figures 1 through 4 comprises cap means 10, formed of substantially rigid material, preferably hard rubber or the like. The cap means 10 has a skirt portion 11, which may have its exterior surface roughened as by the fluting shown at 12 in Figure 1, and the skirt portion may be provided with screw-threads 13 formed on its interior surface. The top wall of the cap means 10 is apertured, and has an annular lip 14 overhanging an annular recess 15, the wall defining the recess 15 merging with a downwardly inclined top wall 16 of an inwardly extending annular projection 17, the lower wall of the projection 17 being substantially flat and providing a shoulder 18. The projection 17 is apertured as shown at 19.

A body 20 is carried by the cap means 10, and is preferably formed of relatively soft resilient

rubber. The body 20 has a circular part 21 fitting within the recess 15 of the cap means 10, and an annular downwardly tapering part 22 closely fitting the inclined wall 16 of the projection 17. The tapering part 22 leads to a cylindrical part 23 which is disposed intermediate the tapering part 22 and an annular flange 24. The flange 24 bears against the shoulder 18 of the cap means 10, and thus holds the body 20 assembled with the cap means 10. The lower surface of the flange 24 tapers downwardly to provide a sealing surface 25. The upper part of the body is provided with a central downwardly inclined recess 27, which is surrounded by a substantially flat annular surface 28. The body is formed with an aperture extending centrally therethrough, and this aperture communicates with the recess 27, and has an enlarged downwardly tapering portion 29 merging with a cylindrical portion 30.

Also carried by the cap means 10 is a bulb means 31, preferably formed of relatively soft resilient rubber. The bulb means 31 has a skirt portion 32, open at its lower end, and having a relatively plane surface 33 at this open end, and an annular groove 34 spaced slightly from the plane surface 33. The skirt 32 merges with a dome-shaped portion 35, the thickness of this dome-shaped portion being less than the thickness of the skirt portion 32, and the connection 30 of the dome-shaped portion 35 with the skirt portion 32 is formed as shown at 36 to facilitate flexing at this point. The dome-shaped portion 35 is provided with a centrally located downwardly tapering valve member 37, preferably integral- 35 ly formed with the bulb means 31, and an upwardly extending knob 38, preferably extending integrally from the outer surface of the dome-shaped portion 35.

Positioned off-center with respect to the bulb means 31, and preferably integrally connected therewith, is an upright boss 39. The boss 39, as herein shown, has its axis somewhat inclined with respect to the axis of the bulb means 31, and is provided with an aperture 40. During manufacture of the bulb means 31, the aperture 40 may be formed with its extremity closed, preferably by an integrally formed plug 41, shown in Figure 3. This plug 41 may be removed to provide for flow through the aperture 40, as by cutting off this plug by means of a knife or scissors, when the dispenser is ready for use. Figures 1, 2, and 4 show the bulb means 31 with the plug removed.

To assemble the parts hereinbefore described, 55

the bulb means 31 is preferably secured to the body 20 in fluid-tight relation, and this may be effected by connecting the plane surface 33 of the bulb means 31 to the plane surface 28 5 of the body 20 by means of a suitable cement or the like, thus forming a unitary structure which includes the bulb means 31 and the body 20. This unitary structure provides a chamber 42, defined by the inner walls of the bulb means 10 10 31 and the upper surface of the body 20. The unitary structure may be assembled with the cap means 10 by inserting the lower end of the body 20 through the aperture 19 in the cap means 10 an amount necessary to pass the flange 15 24 through the aperture 19. The upper surface of the flange 24 then yieldably engages the shoulder 18 of the cap means 10 as shown in Figures 2 and 4, and thus provides a fluid-tight connection between the unitary structure and the cap means 10. At the same time, the lip 14 of the cap means 10 seats in the groove 34 of the bulb means 31, thus assisting to hold the bulb means 31 and the body 20 assembled with the cap means 10. The flange 24 and shoulder 18, and 20 the groove 34 and the lip 14, are so constructed and arranged that plane surfaces 28 and 33 of the body 20 and bulb means 31 respectively, are pressed tightly together, and if desired, the cement joining these plane surfaces may be omitted, 25 so that the body 20 and the bulb means 31 may be assembled individually with the cap means 10.

The combined closure and dispenser thus formed is adapted to cover the opening 43 of a container 44, such as the bottle herein shown. 30 The container 44 may have a neck 45 surrounding the opening 43, and this neck 45 may be provided with exterior screw-threads 46 adapted to engage with the interior screw-threads 13 of the cap means 10, and in this manner hold the combined closure and dispenser in position on the container.

The dome-shaped portion 35 of the bulb means 31 is capable of movement to the position shown in Figure 2, or to the position shown in Figure 4, 35 the dome-shaped portion 35 and its connection with the skirt portion 32 being so constructed and arranged that the dome-shaped portion is yieldably held in either position. In the position shown in Figure 2, the dome-shaped portion 35 is in an extended relation with respect to the skirt portion 32, and in this position the valve member 37 provides for flow of fluid from the container 44, through the aperture in the body 20, 40 to the chamber 42, and through and outwardly of the aperture 40 in the boss 39. The dome-shaped portion 35 may be moved to the position shown in Figure 4, by the application of pressure, such as downward pressure of a finger on the knob 38, 45 thus forcing the dome-shaped portion 35 to a retroverted position with respect to the skirt portion 32, and after the dome-shaped portion 35 has been moved downwardly a predetermined amount, it will snap to its position shown in Figure 4, 50 and will be resiliently held in this position. In the position shown in Figure 4, the valve member 37 enters the aperture in the body 20, and engages the defining surface of the tapered portion 29 in sealing relation, thus preventing fluid from 55 the container to flow to the chamber 42. To move the dome-shaped portion 35 from the position shown in Figure 4 to the position shown in Figure 2, a user may grasp the knob 38 and pull upwardly on this knob, and the dome-shaped portion 35, after it has been moved upwardly a pre- 60

determined amount, will snap to its extended position shown in Figure 2.

To operate the dispenser, assuming that the parts are properly assembled and in the position shown in Figure 2, and assuming also that the 5 container 44 contains a suitable fluid, such as a perfume, a medicinal liquid, or the like, it is merely necessary to invert the container 44, and permit the fluid to gravitate to the chamber 42 and outwardly of the aperture 40 in the boss 39. In some 10 instances it may be necessary to slightly jiggle the container in order to permit air to enter the container through the aperture 40 in the boss 39, so that fluid may flow from the container. After a required amount of fluid has been dispensed, the 15 user may apply pressure to the knob 38, as by pushing with a finger on this knob, to move the dome-shaped portion 35 to its retroverted position, and in this position the valve member 37 seals the opening in the body 20, and thus prevents 20 fluid flow from the container 44. However, it is preferable to return the container 44 to its upright position before moving the dome-shaped portion 35 to its retroverted position, so that any 25 unused fluid in the chamber 42 may drain along the walls of the recess 27, through the aperture in the body 20, and back into the container 44. In this manner, after the dome-shaped member 35 is moved to the position shown in Figure 4, 30 objectionable leaking of unused fluid from the chamber 42 is prevented.

Referring to the embodiment shown in Figures 5 through 8, the embodiment therein illustrated comprises cap means 47, formed of substantially rigid material, preferably hard rubber 35 or the like. The cap means 47 is formed substantially like the cap means 10 hereinbefore described, and has a skirt portion 48 formed with interior screw-threads 49. The top wall of the cap means 47 is apertured, and has an annular lip 50 overhanging an annular recess 51, the wall defining the recess 51 merging with a downwardly inclined top wall 52 of an inwardly extending annular projection 53, the lower wall projection being substantially flat and providing a shoulder 45. The projection 53 is apertured as shown at 55.

A body 56, substantially similar to the body 20 hereinbefore described, is carried by the cap means 47, and is preferably formed of soft resilient rubber. The body 56 has a circular part 50 57 fitting within the recess 51 of the cap means 47, and an annular downwardly tapering part 58, a flange 59, and a downwardly tapering part 60 extending from the flange 59, similar to the part 22, flange 24, and part 25 respectively of the body 55 20, and the body 56 fits the respective parts of the cap means 47 substantially similar to the manner hereinbefore described in the embodiment disclosed in Figures 1 through 4. The upper part of the body 56 is provided with a central downwardly inclined drain recess 61, which is surrounded by a substantially flat annular surface 62. The body 56 is provided with an aperture extending centrally therethrough, and this aperture communicates with the recess 61, and has an enlarged portion 63, a reduced portion 64, and an undercut groove 65 intermediate these portions.

A bulb means 66 is carried by the cap means 47, and is preferably formed of relatively soft 70 resilient rubber. The bulb means 66 has a skirt portion 67, open at its lower end, and having a relatively plane surface 68 at this open end, and an annular groove 69 spaced from the plane surface 68. The skirt portion 67 merges with a 75

dome-shaped portion 70, the thickness of this dome-shaped portion being less than the thickness of the skirt portion 67, and the connection of the dome-shaped portion 70 with the skirt portion 35 is formed as shown at 71, to facilitate flexing at this point. The dome-shaped portion 70 has a projection 72 extending inwardly of the bulb means 66, and this projection is recessed as shown at 73. A valve member 74 is carried by the dome-shaped portion 70, and comprises an elongated stem 75 extending through the aperture in the body 56, one extremity of the stem fitting within the recess 73 formed in the projection 72 and being yieldably grasped by the surface defining the recess 73, and the other extremity of the stem being provided with an enlargement 76 having a tapering surface 77 adapted to engage the surfaces defining the lower end of the aperture portion 64 of the body 56 in sealing relation.

20 Positioned off-center with respect to the bulb means 66, and preferably integrally connected therewith, is an upright boss 78, which is apertured to receive the lower reduced end 79 of a nozzle 80, the aperture of the boss 78 being continued through the skirt portion, as shown at 81, to communicate with the interior of the bulb means 66. The nozzle 80 is preferably formed of rubber, and is provided with an aperture 82, and this aperture may be closed by a plug similar to 30 the integral plug 41 hereinbefore described.

To assemble the parts comprising the embodiment shown in Figures 5 through 8, the bulb means 66, body 56, and the cap means 47, may be assembled in a manner similar to that described in connection with the embodiment shown in Figures 1 through 4, and when assembled, the bulb means 66 and body 56 provide a chamber 83. The stem 75 of the valve member 74 may be inserted through the aperture in the body 56, 40 and its extremity may be seated within the recess 73 of the projection 72. It will be noted that the length of the stem 75 is so proportioned that when the extremity of the stem 75 is properly disposed within the recess 73 of the projection 72, the tapering surface 77 engages the lower end of the body 56 in sealing relation when the dome-shaped portion 70 assumes the shape shown in Figure 6. The reduced extremity 79 of the nozzle 80 may be inserted into the aperture of the boss 78 at any 50 convenient time during assembly operation.

The combined closure and dispenser thus formed is adapted to cover the opening 84 of a container 85, such as the bottle herein shown. The container 85 may have a neck 86 provided 55 with exterior screw-threads 87 adapted to co-operate with the interior screw-threads 49 of the cap means 47, and in this manner hold the combined closure and dispenser in position on the container.

60 To operate the dispenser, assuming that the parts are assembled in the manner shown in Figure 6, and that the container 85 contains a suitable fluid, it is merely necessary to invert the container 85, and to press on the dome-shaped portion 70, as by means of a finger as shown in Figure 8, so that the tapered portion 77 of the valve member 74 is moved from the lower end of the body 56, thus permitting fluid from the container to gravitate into the chamber 83, and 65 through and outwardly of the aperture 82 in the nozzle 80. As before, it may sometimes be necessary to slightly jiggle the bottle to permit air to enter the bottle. Removal of the pressing force from the dome-shaped portion 70 permits the dome-shaped portion 70 to resiliently move from

the shape shown in Figure 8 back to its normal shape shown in Figure 6, so as to seat the valve member and thereby prevent any further fluid flow from the container 85. Any unused fluid within the chamber 83 is preferably permitted to 5 drain along the inclined walls of the recess 61 back through the aperture in the body 56 and into the container 85, as by righting the container 85 and holding the valve member 74 in open position.

10 The invention herein disclosed, provides a combined closure and fluid dispenser which may be easily manufactured and assembled, and may be used for a variety of purposes. The parts comprising the closure and dispenser, if desired, may 15 be of different colors, to provide an attractive appearance.

From the foregoing it will be apparent to those skilled in the art that I have accomplished at least the principal object of my invention, and 20 it also will be apparent to those skilled in the art that the embodiments herein described may be variously changed and modified, without departing from the spirit of the invention, and that the invention is capable of uses and has advantages 25 not herein specifically described; hence it will be appreciated that the herein disclosed embodiments are illustrative only, and that my invention is not limited thereto.

I claim:

1. Closure means for a container, comprising: bulb means, connectable to the container adjacent the container opening, and having a skirt portion and a wall portion capable of being moved to retroverted or extended positions with respect to said skirt portion and including means preventing flow of substance from the container when said wall portion is in retroverted position and providing for flow of substance from the container when said wall portion is in extended 40 position, said wall portion being so constructed and arranged that movement from one position to another is accompanied by a snap action.

2. Closure means for a container, comprising: cap means, engageable with the container adjacent the container opening; sealing means, connected to said cap means, so constructed and arranged as to provide a seal between the connection of said cap means with the container, said sealing means having an opening through which 50 substance from the container may pass; bulb means forming a chamber communicating with said sealing means opening, the chamber having an opening through which substance from the container may be dispensed, said bulb means including a skirt portion connected to said cap means and a wall portion capable of being moved to retroverted or extended positions with respect to said skirt portion, said wall portion being so constructed and arranged that it is movable 55 from one position to another with a snap action and is yieldably held in said other position; and valve means, carried by said wall portion, so constructed and arranged as to close the opening in said sealing means when said wall portion is in retroverted position, and to uncover said opening when said wall portion is in extended position.

3. A dispensing closure for a container, having means engageable with the container for holding the closure in position on the container, 70 and having also a resilient bulb forming a chamber which is adapted to be in communication with the interior of the container, said bulb having a wall portion that may be moved from its extended position to a retroverse position and re- 75

- turn, and said bulb being so constructed and arranged that said wall portion is urged to one or the other of said positions when said wall portion passes through a median or neutral position, 5 said wall portion carrying a valve member so constructed and arranged that in the retroverse position of said wall portion it operates to close communication between said chamber and the interior of the container, and in the extended 10 position of said wall portion it operates to open communication between said chamber and the interior of the container.
4. A dispensing closure for a container, comprising: cap means, engageable with the neck of the container for holding the closure in position on the container; sealing means, of resilient material, carried within said cap means, and engageable with the container neck in sealing relation, said sealing means having a passageway there-through; a bulb formed of resilient material, and carried by the top of said cap means, said bulb providing a chamber which communicates with the interior of the container through the passageway in said sealing means, and said bulb 20 having a wall portion that may be moved from its extended position to a retroverse position and return, said bulb being so constructed and arranged that said wall portion is urged to one or the other of said positions when said wall portion passes 25 through a median or neutral position, and said wall portion carrying a stopper so constructed and arranged that in the retroverse position of said wall portion it fits into and closes the passageway in said sealing means.
5. Closure means for a container, comprising: cap means, having a skirt portion constructed to engage the container adjacent the opening into the container, and having also an apertured top wall, and groove means formed about the interior 30 of said skirt portion; means forming a chamber with said cap means, and having a resilient flange extending through said top wall aperture and peripherally fitting said groove means but occupying only a portion of the cross-sectional extent 35 of said groove means, said chamber having an opening through which substance from the container may be dispensed, and including a movable wall portion; sealing means, constructed and arranged to seal the connection of said cap means 40 with the container, and having an aperture providing for passage of substance from the container to said chamber, and having also a resilient flange peripherally fitting said groove means and so constructed that it closely occupies 45 the remainder of the cross-sectional extent of said groove means and abuts the flange of said chamber forming means in sealing relation, thereby preventing passage of substance outwardly from the container other than through 50 said sealing means aperture to said chamber; and valve means carried by said wall portion, so constructed and arranged that by movement with said wall portion it controls communication between said chamber and the interior of the container.
6. Closure means for a container having a neck surrounding its opening comprising: cap means, having a skirt portion constructed to engage about the container neck, and having also an apertured top wall, and annular groove means formed about the interior of said skirt portion; bulb means formed of resilient material, and forming a chamber with said cap means, and having an integral flange extending through said 70

top wall aperture and peripherally fitting said groove means but occupying only a portion of the cross-sectional extent of said groove means, said chamber having an opening through which substance from the container may be dispensed, 5 and said bulb means having a wall portion movable to different positions; sealing means, formed of resilient material, and having a portion constructed to be clamped between a portion of said cap means and the lip of the container neck, said sealing means having an aperture providing for passage of substance from the container to said chamber, and having also an integral flange peripherally fitting said groove means and so constructed that it closely occupies the remainder of 10 the cross-sectional extent of said groove means and abuts the flange of said bulb means in sealing relation, thereby preventing passage of substance outwardly from the container other than through said sealing means aperture to said chamber; and valve means carried by said wall portion, so constructed and arranged that depending upon the position of said wall portion, it prevents or permits passage of substance 15 through said sealing means aperture. 20

7. Closure means for a container having a neck surrounding its opening comprising: cap means, having a skirt portion constructed to engage about the container neck, and having also an apertured top wall, and annular groove means 25 formed about the interior of said skirt portion; bulb means formed of resilient material, and forming a chamber with said cap means, and having an integral flange extending through said top wall aperture and peripherally fitting said 30 groove means but occupying only a portion of the cross-sectional extent of said groove means, said chamber having an opening through which substance from the container may be dispensed, and said bulb means having a wall portion so 35 constructed that it may be moved from an extended position to a retroverse position and return, and said bulb means being so constructed and arranged that said wall portion is urged to one or the other of said positions when said wall 40 portion passes through a median or vertical position; sealing means, formed of resilient material, and having a portion constructed to be clamped between a portion of said cap means and the lip of the container neck, said sealing means having an aperture providing for passage of substance from the container to said chamber, and having also an integral flange peripherally fitting said groove means and so constructed that it closely occupies the remainder of the cross-sectional extent of said groove means and abuts the flange of said bulb means in sealing relation, thereby preventing passage of substance outwardly from the container other than through 45 said sealing means aperture to said chamber; and valve means carried by said wall portion, so constructed and arranged that in retroverse position of said wall portion said valve means closes 50 passage through said sealing means aperture, and in extended position of said wall portion said valve means provides for passage through said sealing means aperture. 55

8. Closure means for a container having a neck surrounding its opening comprising: cap means, 70 having a skirt portion constructed to engage about the container neck, and having also an apertured top wall, and annular groove means formed about the interior of said skirt portion; bulb means formed of resilient material, and 75

- forming a chamber with said cap means, and having an integral flange extending through said top wall aperture and peripherally fitting said groove means but occupying only a portion of the cross-sectional extent of said groove means, said chamber having an opening through which substance from the container may be dispensed, and said bulb means having a wall portion resiliently urged to a predetermined portion, but movable from such position by the application of manual force; sealing means, formed of resilient material, and having a portion constructed to be clamped between a portion of said cap means and the lip of the container neck, said sealing means having an aperture providing for passage of substance from the container to said chamber, and having also an integral flange peripherally fitting said groove means and so constructed that it closely occupies the remainder of the cross-sectional extent of said groove means and abuts the flange of said bulb means in sealing relation, thereby preventing passage of substance outwardly from the container other than through said sealing means aperture to said chamber; and valve means carried by said wall portion, so constructed and arranged that when said wall portion is in said predetermined position said valve means closes passage through said sealing means aperture, and when said wall portion is moved from said predetermined position said valve means provides for passage through said sealing means aperture. 15

THOMAS W. MILLER.
